(57) **CLAIM**

The ornamental design for an automatic transfer switch, as shown and described.

DESCRIPTION

1. Automatic transfer switch

1.1 : Front perspective view

1.2 : Front

1.3 : Back

1.4 : Left

1.5 : Right

1.6 : Top

1.7 : Bottom

Reproduction 1.1 is a front perspective view of the automatic transfer switch; reproduction 1.2 is a front view thereof; reproduction 1.3 is a back view thereof; reproduction 1.4 is a left view thereof; reproduction 1.5 is a right view thereof; reproduction 1.6 is a top view thereof; and reproduction 1.7 is a bottom view thereof.

The broken lines depict portions of the automatic transfer switch that form no part of the claimed design.

1 Claim, 7 Drawing Sheets
